Application filed May 2, 1899. Serial No. 715,367. Term of patent 14 years.

To all whom it may concern:

Be it known that I, ALEXANDER PEGGIE BLYTH, a subject of the Queen of Great Britain, residing at 46 to 53 Quality street, Leith, 5 Scotland, have invented and produced a new and original Design for Bottles, of which the following is a specification, reference being had to the accompanying drawing, forming a part thereof, and being a perspective view of 10 a bottle embodying my new design.

As shown in the drawing, my design consists of a pyramid-shaped bottle with rounded corners merging into a frusto-conical por-

tion surmounted by a neck of cylindrical form of somewhat larger diameter than the top of 15 the upwardly-converging body of the bottle.

Having thus described my invention, what I claim as new, and desire to secure by Letters Patent, is—
